UNITED STATES PATENT OFFICE.

WILLIAM H. OLVER, OF OSHKOSH, WISCONSIN.

IRONING-MACHINE.

No. 902,676.

Specification of Letters Patent.

Patented Nov. 3, 1908.

Application filed September 5, 1907. Serial No. 391,490.

To all whom it may concern:

Be it known that I, WILLIAM H. OLVER, a citizen of the United States, residing at Oshkosh, in the county of Winnebago and State 5 of Wisconsin, have invented a new and useful improvement in ironing-machines for the use of tailors and those doing pressing with sad-irons, of which the following is a specification.

10 My invention relates to improvements in the mechanism for relieving the person doing the pressing work upon garments from a portion of the weight of the sad iron, by suspending it by means of a spring connection 15 from a tandem trolley which is arranged for running upon a track placed above and parallel with the press table and its stand, and the object of the improvement is to produce a practicable device that can be furnished at 20 such a low cost as to be within the reach of all persons doing such work, and a device that can be easily installed in any room where pressing of garments is carried on.

My improvement is illustrated in the accompanying drawing, in which,—

Figure 1 is a side elevation of the side of a pressing table, a press stand thereon, a sad iron, the ceiling of a room in vertical section, a track rail suspended from the ceiling, a 30 tandem trolley upon said rail and a spring connection between the trolley upon said rail and the sad iron. Fig. 2 is an elevation showing the end of the press table with all of the parts shown in Fig. 1 in the position they 35 appear from such end view. Fig. 3 is a vertical section of the spring connection, broken into two parts for want of room, which I employ for a connection between the trolley and sad iron. Fig. 4 is a side elevation of the 40 same turned one quarter around, and one of the collars upon it in a higher position, and having a strap connection, broken for want of room, below the spring device. Fig. 5 is a side elevation of a hanger in which the track 45 rail is supported. Fig. 6 is a plan of the tandem trolley wheels in their hanger. Fig. 7. is an edge view of a trolley wheel and a transverse section of a track rail formed of wood. Fig. 8 is an edge view of a trolley wheel of a 50 modified form from that shown in Fig. 7, and a transverse section of a track rail formed of a metallic bar. Fig. 9 is a plan of a screw eye, which may be used in suspending the sad iron from the spring device. Fig. 10 is 55 an end view of a stirrup handle, used in suspending the sad iron from the spring connec-

tion. Fig. 11 is an edge and side elevation of the straps for adapting the device to rooms of different heights one being longer than the other. Figs. 3 to 11 inclusive, are upon a 60 larger scale than the two others.

Similar numerals and letters indicate like parts in all of the views.

1, indicates a tailor's press table; 2, a press stand thereon; 3 a sad iron having a handle 65 4; 5, a sad iron stand, which may be a sheet of asbestos paper, or other suitable material; 6, the ceiling of a room from which the trolley track rail is suspended; 7, 7, two pieces of wood to be secured to the ceiling of 70 a room, and to each one of which one of the supporting hangers 8 is to be attached with screws 9. In rooms ceiled with wood ceiling, the hangers can be screwed directly to the ceiling, the pieces 7 being dispensed with. 75

The hangers are easiest made from a strip of band iron, bent into the form shown in Fig. 5, the rail 10 or 10^a, being laid into the rail seat 8^a and where it may be secured from endwise movement by inserting a pin 12 80 through the hanger and rail, see Figs. 1 and 5. This track rail may be of wood, as in Figs. 1 and 7, or of metal as 10^a, of Fig. 8. It is desirable that either the rail or trolley 85 wheels be made of wood, or some non-metallic material, so that the running of the wheels over the track may be as near noiseless as possible. The trolley wheels 11 or 11^a, whichever is used, I arrange in a hanger, as 13, in a tandem manner, as experience has 90 demonstrated the superiority of this arrangement over that of a single wheel in evenness of running.

The hangers may be of any suitable style, such as is shown in Figs. 1, 2 and 6 being well 95 suited for the purpose, it being formed of band metal of a suitable dimension, with a spacing block 14 between the two hanger pieces, 13^a and 13^b; rivets or bolts 15, being inserted through both pieces and the spacing 100 block, and bolts 16, inserted through said pieces and the trolley wheels. The connection between the trolley hanger and sad iron consists of several parts which are connected together in such a manner as to make some 105 of them adjustable as regards length.

A tube 17 is provided, having inside of it a spiral spring, 18, which when contracted, is perhaps two thirds of the length of said tube. Its coils are wound close together and its resiliency is made effective by pulling the ends apart. Each end of the coil is provided with 110

an eye, 19, through the upper one of which a bolt 20 is inserted, the bolt passing through slots 21 which are cut a suitable length through opposite sides of the tube, the bolt 5 being provided with a thumb nut 20^a, for securing the bolt, and consequently the upper end of the spring in the desired vertical position, by screwing the thumb nut on tightly, as more or less of the stretch of the spring is 10 desired. The upper end of the tube is provided with a bolt 22, which passes through it for suspending the tube by means of the strap 23, from the hanger 13. This connecting device may be of metal or of some flexible 15 material. The lower end of the spring is connected to the tube by a bolt 24, which passes through the slots 25, and is provided with a nut 24^a, the slots being cut through opposite sides of the tube, and a collar 26, loose 20 enough to slide up and down easily being placed upon the tube and through which the bolt 24 passes for the free movement of the bolt, as the spring in the use of the device plays up and down. This collar is shown in 25 Figs. 1, 2 and 3, at its lowest limit and the spring as being (in Fig. 3,) stretched to some extent, but in Fig. 4 it is at the upward limit of the slot 25. A collar 27, provided with a clamp screw 27^a, is secured to the tube for 30 limiting the downward movement of the spring. By moving this collar upward upon the tube, the extent of the stretch of the spring is lessened, and by lowering it its extent is increased. Attached to the bolt 24 is 35 a link 28, which is extended downward and is connected by means of the connection 29, which connection is preferably as shown, a leather strap, with the stirrup handle 30. This stirrup handle may be formed of a piece 40 of band iron, has holes 31, near each end and a rivet pin 32 at its mid-length for securing one end of the strap to it at 33, and a knob 34, upon which to connect the other end of the strap, the strap being provided with a plurality 45 of slits, or button holes 35 for buttoning over the knob 34. Extending downward from the holes 31, are connections 36, which extend to and connect with the handle 4 of the sad iron, by means of screw eyes 37, which are screwed 50 into the handle. These connections may be a wire, but are preferably of a flexible material, as a rope of wire or hemp.

For adapting the device for rooms of different height, straps 23, of different length 55 are supplied, all the other parts being adapted for any height of room. In suspending the sad iron from the stirrup handle 30 by the connections 36, upon raising one end of the sad iron more than the other, the spring 60 equalizes the amount of weight at the ends of the sad iron which the person using it is relieved of, and makes the handling of the sad iron easier. Another important part is the adjustment of the collar 27, which can be 65 regulated to prevent the sad iron from drop-

ping more than about one inch below the level of the press stand, and then to carry the total weight of it while it is not in use, and thereby doing away with the necessity of a stand to rest the iron upon while not using it. It 70 saves the labor of lifting the iron from the table to the press stand.

Some work of tailors requires heat in the iron and a rapid movement of it, more than it does weight, and consequently, the person 75 doing the pressing is required to carry the larger part of this weight, and often for a long time, which then useless weight, this improvement is designed to relieve the person of, who is doing the pressing. For adjusting 80 the amount of weight to be carried, for a long period of time in pressing, the adjustment can be made by raising or lowering the bolt 20, but for any sudden requirement, the adjustment can be made by means of changing 85 the length of the strap, on the knob 34.

The device is to be used as follows:—Adjustment of the spring in accordance with the weight that the operator is desirous of being relieved of, having been made, the operator 90 grasps the sad iron handle in the usual manner and lifts it up to the work upon the press stand and moves it back and forth upon the work in hand in the usual manner, the trolley following every back and forth movement, 95 and it being much easier to bear down than to lift up, any desired pressure can be applied upon the work with much less fatigue than if the entire weight of the sad iron had to be carried.

Having described my invention, what I 100 claim and desire to secure by Letters Patent, is,—

1. In a device for relieving the user of part of the weight of the sad iron in pressing garments, a single track rail suspended from a fixed surface parallel with and above the pressing table, a single pair of trolley wheels mounted tandem upon said track rail, a hanger depending from said pair of tandem 110 trolley wheels, and a connection between said trolley wheel hanger and the sad iron consisting of several separate sections, one of which is detachable, and one of which comprises a tube, a coiled spring arranged within the 115 tube, the upper end of which spring is provided with means for its connection with and vertical adjustment upon said tube, and its lower end having an easy moving and limited vertical movement thereon.

2. In a device for relieving the user of part of the weight of the sad iron in pressing garments, two hangers adapted to be secured to the ceiling of a room in which the device is used, a single track rail adapted to be mounted in said hangers and suitably secured therein, a single pair of trolley wheels mounted tandem within a suitable hanger and adapted to roll along upon said track rail, one of the parts, the wheels or the track rail, being 125 130

- formed of a non-metallic material, and a connection between the trolley wheel hanger and sad iron consisting of a plurality of separable sections, one of which comprises a tube, a coiled spring within the tube, the upper end of which spring has a vertically adjustable connection with said tube, and its lower end an easily movable, limited vertical movement therein.
- 10 3. In a device for relieving the user of part of the weight of the sad iron in pressing garments, a track rail adapted for suspension in suitable hangers from a fixed surface above and parallel with the pressing table, a trolley device arranged in a suitable hanger and adapted to be rolled along said track rail, and a connection between the trolley hanger and sad iron consisting in part of a tube with which the hanger and sad iron are connected,
- 15 20 a spiral spring connected to said tube inside thereof near its upper end, means for adjusting the upper end of said spring vertically within the tube, a link connecting with the lower end of said spring by means of a bolt
- 25 passing through one end of said link and through slots in opposite sides of the tube, and a suitable connection between the lower end of said link and the sad iron.
4. In a device for relieving the user of part

of the weight of the sad iron in pressing garments, a track rail adapted for suspension from a fixed surface above, and parallel with the pressing table in suitable hangers, a trolley device arranged in a suitable hanger and adapted to be rolled along said track rail, a connection between said hanger and the sad iron, consisting in part of a tube, a suitable connection for connecting the hanger and tube, a spiral spring arranged inside of said tube and adjustably connected with the tube at its upper end, a link connecting with its lower end by means of a bolt which passes through slots arranged lengthwise of the tube in opposite sides thereof and is easily movable lengthwise of said slots, a connection between said link and the stirrup handle of the sad iron, connections extending downward from each end of said stirrup handle to opposite ends of the sad iron handle, and a collar arranged for vertical adjustment on said tube below said spring for limiting the downward movement of the lower end of said spring.
